UNITED STATES PATENT OFFICE.

HIRAM H. BOYCE, OF CHICAGO, ILLINOIS.

PULLEY.

SPECIFICATION forming part of Letters Patent No. 738,765, dated September 15, 1903.

Application filed January 26, 1903. Serial No. 140,641. (No model.)

To all whom it may concern:

Be it known that I, HIRAM H. BOYCE, a citizen of the United States of America, and a resident of Chicago, in the county of Cook and State of Illinois, have invented certain new and useful Improvements in Pulleys, of which the following is a specification.

The main objects of my invention are to provide improved means for securing together the parts of a split pulley, to provide suitable construction whereby such means will be efficient for the purpose and will be readily accessible from the side of the pulley, and to provide fastening means of a type which will permit of their application to a pulley of comparatively small diameter when such pulley is applied to a relatively large shaft. I accomplish these objects by the device shown in the accompanying drawings, in which—

Figure 1 is a side elevation of a wooden split pulley having fastening means constructed according to my invention. Fig. 2 is a section on the line 2 2 of Fig. 1. Fig. 3 is a perspective view of one of the yokes. Fig. 4 is a section of same on the line 4 4 of Fig. 3. Fig. 5 is a perspective view of one of the rim-sections and its gripping-block.

In the construction shown the rim 1 of the pulley is formed of two sections 3, separable along the line 4. Each of the rim-sections 3 has rigidly secured therein a gripping-block 5, provided with a concave gripping-surface 6, adapted to engage a shaft. Each of the gripping-blocks 5 is provided with a slot 7, extending entirely through same. A yoke 8 is seated in each of the slots 7. The yokes 8 are exactly alike in structure, one end 9 of each being forked, as will be seen in Fig. 2, and adapted to engage the adjacent end 10 of the other yoke. The adjoining ends of the yokes 8 are secured together by means of transverse pins or cotters 11. The yokes 8 serve as binding members for securing the two rim-sections 3 together and are of suitable form to span the shaft and to extend over the wedges 12. Each of the wedges 12 is seated in a channel 13, which extends transversely across the middle part of the gripping-block 5 on the side which is opposite to the gripping-surface 6 of such block. The smaller end of each of the wedges 12 terminates in a threaded shank 14, which passes through a bearing-

piece 15 and has mounted thereon a nut 16. The bearing-piece extends along the sides of the wedge 12, so as to bear upon the adjacent part of the yoke 8. The bearing-piece 15 avoids the necessity of having a deep channel 13 in the block 5 in order to get sufficient bearing-surface for the nut 16.

The operation of the device shown is as follows: When the pulley is to be applied to the shaft, the yokes 8 are seated in the slots 7 of their respective gripping-blocks, and the wedges 12, together with the bearing-pieces 15 and the nut 16, are loosely assembled in their proper positions. The rim-sections 3 are now placed around the shaft, and the adjacent ends 9 and 10 of the yokes 8 are secured together by means of the pins 11. The nuts 16 are finally tightened upon the shanks 14, drawing the wedges 12 along the channels 13 and through the bearing of such wedges on the yokes 8, forcing the gripping-blocks 5 toward each other and securely clamping the device upon the shaft.

It will be seen that by the construction shown the pressure of the wedges 12 is exerted at the middle part of the gripping-blocks and directly over the center of the gripping-surfaces 6. The pulley may be readily removed from the shaft by simply loosening the wedges 12 and withdrawing the pins 11.

It will be seen that some of the details of the construction shown may be altered without departing from the spirit of my invention. I therefore do not confine myself to such details except as hereinafter limited in the claims.

What I claim as my invention, and desire to secure by Letters Patent, is—

1. A pulley, comprising a rim; a pair of blocks secured within the rim, and having opposite gripping-surfaces for a shaft, one of the blocks having a slot extending through same on each side of its gripping-surface; a binding member seated in said slots having a part extending through said slotted block at each side of said gripping-surface and secured to the other block; an adjustable wedge extending transversely of said binding member, said wedge bearing between said binding member and said slotted block, and having a threaded shank extending transversely of the web of the pulley; and a nut on said

shank adapted to draw said wedge between said binding member and said slotted block and thereby draw said blocks toward each other, substantially as described.

5. 2. A pulley, comprising a pair of separable rim-sections; a block secured within each of said rim-sections and having a gripping-surface adapted to grip a shaft, one of said blocks having therein a channel for a wedge 10 extending across same in a direction substantially parallel to the axis of said rim; a wedge seated in said channel and having a threaded shank at one end of same; a yoke passing over said wedge and having a part extending 15 along said block at each side of said gripping-surface; means for removably securing said yoke to the other of said blocks; and a nut on said shank adapted to cause said wedge to bear between said yoke and said 20 first block and thereby draw said blocks toward each other, substantially as described.

3. A pulley, comprising a pair of separable rim-sections; a block secured within each of said rim-sections and having a gripping-surface 25 adapted to grip a shaft, one of said blocks having therein a channel for a wedge extending across same in a direction substantially parallel to the axis of said rim and having a slot extending through same transversely of 30 said axis; a wedge seated in said channel and having a threaded shank at one end of same; a yoke seated in said slot, passing over said wedge and having a part extending along said block at each side of said gripping-surface; 35 means for removably securing said yoke to the other of said blocks; and a nut on said shank adapted to cause said wedge to bear between said yoke and said first block and thereby draw said blocks toward each other, 40 substantially as described.

4. A pulley, comprising a pair of separable rim-sections; a block secured within each of said rim-sections and having a gripping-surface for a shaft; there being slots extending 45 through said blocks on each side of said gripping-surfaces; a pair of wedges one mounted on each of said blocks and each having a threaded shank disposed transversely of the web of the pulley; a pair of yokes, one passing over each of said wedges, and each having a part extending through the slots in its corresponding block at each side of said grip-

ping-surface; means for readily connecting the adjacent ends of said yokes; and nuts mounted on said threaded shanks and adapted 55 to cause said wedges to bear between their respective blocks and yokes for drawing said blocks toward each other, substantially as described.

5. A pulley comprising a pair of separable 60 rim-sections; a block secured within each of said rim-sections and having a gripping-surface for a shaft; there being slots extending through said blocks on each side of said gripping-surfaces; a pair of wedges, one mounted 65 on each of said blocks and each having a threaded shank disposed transversely of the web of the pulley; a pair of yokes, one passing over each of said wedges, and each having a part extending through the slots in its corresponding block at each side of said gripping-surface; removable pins for readily connecting the adjacent ends of said yokes; and nuts mounted on said threaded shanks and 70 adapted to cause said wedges to bear between their respective blocks and yokes for drawing said blocks toward each other, substantially as described.

6. A pulley, comprising a rim; a pair of blocks secured within the rim, and having opposite gripping-surfaces for a shaft, one of the blocks having a slot extending through same on each side of its gripping-surface; a yoke seated in said slots having a part extending through said slotted block at each side of said 85 gripping-surface and secured to the other block; an adjustable wedge extending transversely of said binding member, said wedge bearing between said binding member and said slotted block, and having a threaded 90 shank extending transversely of the web of the pulley; a nut on said shank adapted to draw said wedge between said binding member and said slotted block and thereby draw said blocks toward each other; and a bearing-piece extending along said wedge and acting between the nut and said yoke, substantially as described.

Signed at Chicago this 22d day of January, 1903.

HIRAM H. BOYCE.
